CAMERA LENS MOUNTING ADAPTOR

Ben Kleinerman, New Hyde Park, N.Y., assignor to
Tiffen Manufacturing Corp., Roslyn Heights, N.Y.

Filed Sept. 10, 1973, Ser. No. 395,752

Term of patent 7 years

Int. Cl. D16—05

U.S. Cl. D61—1 E

FIG. 3

FIG. 4

FIG. 1

FIG. 2

FIG. 7

FIG. 5

FIG. 6

FIG. 1 is a front elevational view of a camera lens mounting adaptor showing my new design;

FIG. 2 is a top plan view thereof;

FIG. 3 is a left side elevational view thereof, the right side being substantially a mirror image thereto;

FIG. 4 is an enlarged fragmentary sectional view taken substantially along the lines 4—4 of FIG. 1;

FIG. 5 is a rear elevational view thereof;

FIG. 6 is a bottom plan view thereof; and

FIG. 7 is a front perspective view thereof.

I claim:

The ornamental design for a camera lens mounting adaptor, substantially as shown and described.
